(57) **CLAIM**

The ornamental design for an electric toothbrush handle, as shown and described.

DESCRIPTION

FIG. 1 is a perspective view of a first embodiment of an electric toothbrush handle showing our new design;

FIG. 2 is a front view of the electric toothbrush handle shown in FIG. 1;

FIG. 3 is a right side view of the electric toothbrush handle shown in FIG. 1;

FIG. 4 is a back view of the electric toothbrush handle shown in FIG. 1;

FIG. 5 is a left side view of the electric toothbrush handle shown in FIG. 1;

FIG. 6 is a top view of the electric toothbrush handle shown in FIG. 1;

FIG. 7 is a bottom view of the electric toothbrush handle shown in FIG. 1;

FIG. 8 is a perspective view of a second embodiment of an electric toothbrush handle showing our new design;

FIG. 9 is a front view of the electric toothbrush handle shown in FIG. 8;

FIG. 10 is a right side view of the electric toothbrush handle shown in FIG. 8;

FIG. 11 is a back view of the electric toothbrush handle shown in FIG. 8;

FIG. 12 is a left side view of the electric toothbrush handle shown in FIG. 8;

FIG. 13 is a top view of the electric toothbrush handle shown in FIG. 8;

FIG. 14 is a bottom view of the electric toothbrush handle shown in FIG. 8;

FIG. 15 is a perspective view of a third embodiment of an electric toothbrush handle showing our new design;
FIG. 16 is a front view of the electric toothbrush handle shown in FIG. 15;
FIG. 17 is a right side view of the electric toothbrush handle shown in FIG. 15;
FIG. 18 is a back view of the electric toothbrush handle shown in FIG. 15;
FIG. 19 is a left side view of the electric toothbrush handle shown in FIG. 15;
FIG. 20 is a top view of the electric toothbrush handle shown in FIG. 15;
FIG. 21 is a bottom view of the electric toothbrush handle shown in FIG. 15;
FIG. 22 is a perspective view of a fourth embodiment of an electric toothbrush handle showing our new design;

FIG. 23 is a front view of the electric toothbrush handle shown in FIG. 22;
FIG. 24 is a right side view of the electric toothbrush handle shown in FIG. 22;
FIG. 25 is a back view of the electric toothbrush handle shown in FIG. 22;
FIG. 26 is a left side view of the electric toothbrush handle shown in FIG. 22;
FIG. 27 is a top view of the electric toothbrush handle shown in FIG. 22; and,
FIG. 28 is a bottom view of the electric toothbrush handle shown in FIG. 22.
The broken lines depict portions that form no part of the claimed design.
